[57] CLAIM

The ornamental design for a chiropractic car seat, or similar article, as shown and described.

DESCRIPTION

FIG. 1 is a top plan view of a chiropractic car seat, or similar article, showing my new design;

FIG. 2 is a side elevational view;

FIG. 3 is a front elevational view;

FIG. 4 is a bottom plan; and

FIG. 5 is a rear elevational view.

The side of the car seat not shown is a mirror image of the side shown.
